UNITED STATES PATENT OFFICE.

THOMAS DOWNHAM NUTTALL, OF BURY, ENGLAND.

STEAM-UTILIZING PLANT.

1,247,566.

Specification of Letters Patent. Patented Nov. 20, 1917.

Application filed May 5, 1915. Serial No. 26,054.

To all whom it may concern:

Be it known that I, THOMAS DOWNHAM NUTTALL, a subject of the King of Great Britain, residing at Park View, Walmersley 5 Road, Bury, in the county of Lancaster, England, have invented new and useful Improvements in Steam-Utilizing Plants, of which the following is a specification.

My invention relates to apparatus employing steam both for motive power and for drying, or other analogous purpose, in cases where two, or more, machines and their adjuncts are employed, and the object of my invention is to effect economy and efficient utilization 10 of power and heat in the working of such apparatus by arranging, as far as is practical, an equipoise between the power and heat requirements of the apparatus, under varying conditions of work, the arrangement being such that the operation of the apparatus is facilitated by enabling either, or any, of the machines, or of the combination of machines constituting units, to be run, if desired, at any required speed relatively 15 to the other machine, or unit, or machines, or units, and so that any machine, or unit, can be kept in operation pending repair of its main driving means.

My invention is intended more especially 20 for use in connection with paper-making apparatus and I will describe it as employed in such connection from which its other analogous applications will also be understood.

According to my invention, instead of, as 25 usual, driving the whole of the pulp-preparing devices of the apparatus such as kneaders, breakers, beaters, refiners, and general preparatory devices from one power generating center such as one large steam engine, 30 turbo-generator, or other source of power and driving the paper-making parts proper, such as the pumps, the stuff-chest stirrers, wire traverse and shake, wet presses, drying cylinders and calenders and also the 35 winders, if such be used, of the several machines by separate steam engines, or by electrical motors taking their current from the main generating center, I provide a separate steam engine, for driving the said pulp-preparing 40 devices, appertaining to each machine (or unit constituted by two, or more, combined machines) and for providing power for driving the paper-making parts proper, of all of the several machines, or

units, these separate steam engines being supplied with steam from one common steam supply pipe, and the said engines, or any desired number of them, exhausting their steam into one common exhaust pipe from which branches lead to the respective drying cylinders, the motion for the paper-making parts proper of each machine, or unit, being obtained from electric motors, respectively for the variable speed portion and for the constant speed portion, the said motors receiving their current from an electric distributor or switch board supplied by electric generators driven from the aforesaid several steam engines the electric connections of these electric generators being carried to a distributor or switch-board, or the like, common to all, so that electric current can be conveyed from this common source to all, or any, of the first mentioned electric motors to operate all, or any required number, of the several paper-making machines, or units, as required, each variable speed motor being of any known or suitable kind provided with shunt resistances by which the speed of driving each machine, or unit, can be regulated as required as is well known. The exhaust steam from the several steam engines, or from any required number of them, is, as aforesaid, conveyed to one common exhaust pipe and thence to the respective drying cylinders, the steam passages being so controlled, by valves, or the like, that the steam from the said exhaust pipe can be conveyed to all, or any, of the drying cylinders as may be required.

The common steam pipe and the common exhaust pipe are connected with each other by a pipe, or passage, provided with an automatic valve which opens on the pressure in the supply of exhaust steam to the drying cylinders decreasing below any predetermined point so that live steam to keep up the requisite pressure, is then automatically supplied from the live steam pipe. The common exhaust pipe is provided with an automatic relief-valve which will open if the supply of exhaust steam to the drying cylinders should increase above a predetermined amount, for instance if the supply of exhaust steam should exceed the requirements of the drying cylinders. The excess steam which thus passes through the relief-valve may be delivered to any required

place, such, for instance, as to the hot-well for supplying the steam boilers, or to the atmosphere.

By connecting, or linking, together the steam engines, both as regards their output of power and their output of heat as represented by the exhaust steam, I obtain a practical equipoise between the power requirements and the heat requirements of the apparatus as a whole under the varying conditions which apply in work.

By my invention I minimize stoppage due to breakdown; for instance, if the engine, or motor, of any machine, or unit, should fail, those of the other machines, or units, can temporarily take up the work of that particular machine, or unit, if the driving means be suitably proportioned, because if, for example, in paper-making apparatus, an engine of one machine, or unit, should fail its paper-making parts proper can temporarily take current from the common electric distributor, or switch-board and the pulp-preparing devices, appertaining to such machine, or unit, can be coupled up, by any suitable arrangement of clutches and shafting so as to be driven temporarily from the engine, or engines, of the other machine, or unit, or machines, or units. Or the pulp-preparing devices may be driven indirectly from the steam engines through electric motors obtaining their current from the common electric distributor, or switch-board so that, if the engine of a machine, or unit, should fail, the pulp-preparing devices thereof can be temporarily driven by current obtained from the common electric field. In either case efficiency of the apparatus as a whole will be maintained.

40 A great advantage of an arrangement according to my invention is the efficiency and economy due to the balancing of the power and heat requirements of the installation, whereby, under all ordinary working conditions, the maximum of power and of drying, or analogous effects, will be obtained from the steam.

It will be understood that the requirements, as regards driving and heat, will vary with varying conditions, such as, for instance, in paper-making apparatus, the class of paper being made. Where great heat is required all the steam engines may be non-condensing engines as all their exhaust steam can be utilized in the drying cylinders, but where the heat required is relatively small some of the steam engines may be condensing engines, or other prime motors.

60 The accompanying drawings are diagrammatic plans illustrating arrangements in accordance with my invention, Figure 1 illustrating an arrangement of six units of one machine each wherein the pulp-preparing devices are driven direct from the steam en-

gines and Fig. 2 illustrating an arrangement, (in which four units of one machine each are shown) wherein the pulp-preparing devices are operated by electric motors driven by electric current obtained from a common distributor, or switchboard supplied by translating devices driven by the steam engines. Fig. 3 is a section of a clutch and pulley connection, as hereinafter described.

75 These diagrams are only examples of how arrangements according to my invention as defined by the claims, may be carried out, and I do not, of course, limit my claims of invention to these precise arrangements.

80 Referring first to Fig. 1; A¹ to A⁶, represent the pulp-preparing devices, a¹ to a⁶ the pulp vats, and B¹ to B⁶, the paper-making parts proper, of the respective units. I provide a number of non-condensing steam engines (C¹ to C⁶), corresponding to the number of units A¹ to A⁶, and B¹ to B⁶. The pulp-preparing devices, appertaining to the respective units, are driven by any suitable gear, as indicated at d¹ to d⁶. The said steam engines also drive electric generators e¹ to e⁶, from which the electric current is taken by the leads f¹ to f⁶, to a common switch-board at G, which may be of any ordinary kind. Current is taken from this common source by leads h¹ to h⁶, to constant speed electric motors (indicated at i¹ to i⁶), which drive the devices of the paper-making parts proper which require to be driven at constant speed. Current is also taken from the said common source to variable speed electric motors (indicated at j¹ to j⁶) which drive the devices of the paper-making parts proper which require to be driven at variable speed.

95 The steam engines C¹ to C⁶, are supplied with steam from a live steam pipe L, common to all and the exhaust pipes m¹ to m⁶ from the said steam engines lead to a pipe M, common to all, and from this pipe M, branch pipes, n¹ to n⁶, lead to the drying cylinders indicated at N¹ to N⁶. Between the live steam pipe L, and the exhaust pipe M, is a communicating pipe P, provided with an automatic valve p, for the purpose 100 aforesaid.

105 In Fig. 2 the parts which correspond with those shown in Fig. 1 are marked with the same letters of reference. The steam engines C¹ to C⁴, instead of driving the pulp preparing parts directly, drive only the electric generators Q¹ to Q⁴, from which leads q¹ to q⁴ take current to the switch-board at G, and, from this proceed leads s¹ to s⁴ which feed the electric motors r¹ to 115 r⁴, which respectively drive the pulp-preparing parts of each unit, the current for driving the paper-making parts proper being also taken from the said switch-board as in the arrangement Fig. 1.

It will be readily understood that the various driving means can be provided with any suitable arrangements of clutches by which they can be connected with, and disconnected from, each other as required so that, for instance, if a steam engine should break down the parts of the unit which it worked can be temporarily worked by power supplied by, or from, the other steam engines. This is effected by the steam engines transmitting their power to the line shaft, common to all, by means of the pulleys t^1 to t^6 which are arranged each with a friction clutch so that the pulleys can be connected with, or disconnected from the said shaft as desired. Fig. 3 is a section of one of these combined pulleys and clutches. t is the pulley. u is the outer casing of the friction clutch on which the pulley is secured. v is the fixed bracket secured to the main housing of the shaft, w is the circular fixing bolted to the said bracket on which the pulley t rotates. When the pulley is disconnected from the shaft only the internal part of the friction clutch rotates and when the clutch is engaged the pulley is in driving connection with the shaft.

In cases where more power is required than is obtainable from the steam used for heating, the extra power can be obtained from any suitable motors such as condensing steam engines, or gas, or oil, engines and in cases where more heat is required than is supplied by the exhaust steam from the non-condensing steam engines the extra heat can be obtained from live steam, or from other available source, and it will be readily understood that other variations in the general arrangements can be made without departing from the nature of my invention.

What I claim is:—

1. In a steam utilizing plant, a group of steam driven engines, a group of electric generators driven thereby, a current distributor common to said generators, a group of electric motors connected to said distributor, a group of independent working apparatus driven by said motors, a common exhaust from said steam engines and a group of independent utilizing apparatus connected to said common exhaust, whereby upon the failure of portion of the steam driven

engines the operation of the working apparatus and exhaust steam utilizing apparatus of the plant will not be interrupted. 55

2. In a steam utilizing plant, a group of independent working apparatus, an operating power source common thereto, a group of independent steam engines furnishing power in common to said source, a common exhaust 60 from said engines, and a group of utilizing apparatus connected to said common exhaust, whereby upon the failure of a part of said steam engines, the work thereof is assumed by the remainder and the operation 65 of the plant as a whole maintained without interruption, substantially as described.

3. In a steam utilizing plant, a group of heavy-service units, a group of steam driven engines for operating the same, a group of 70 electric generators driven by said engines, a current distributor common to said generators, a group of light-service units, a group of electric motors connected to said distributor for operating said light-service 75 units, a common exhaust for said steam engines and a group of steam utilizing units connected to said common exhaust, whereby upon the failure of portion of the steam driven engines the operation of the various 80 units will not be interrupted.

4. In a steam utilizing plant, a group of steam driven engines, a transmission system common thereto, a group of heavy-service units driven through said transmission system, a group of electric generators driven by said engines, a current distributor common to said generators, a group of light-service units, a group of electric motors connected to said distributor for operating said 90 light-service units, a common exhaust for said steam engines and a group of steam utilizing units connected to said common exhaust, whereby upon the failure of portion of the steam driven engines the operation of 95 the various units will not be interrupted.

In testimony whereof I have signed my name to this specification in the presence of two subscribing witnesses.

THOMAS DOWNHAM NUTTALL.
